UNITED STATES PATENT OFFICE

137,663

DESIGN FOR A COMBINED DOOR AND PUSH-GRILLE

Dallas Emery Walker, Tampa, Fla.

Application February 18, 1944, Serial No. 112,632

Term of patent 14 years

(Cl. D13—1)

To all whom it may concern:

Be it known that I, Dallas Emery Walker, a citizen of the United States of America, residing at Tampa, in the county of Hillsborough, State of Florida, have invented a new, original, and ornamental Design for a Combined Door and Push-Grille, of which the following is a specification, reference being made to the accompanying drawing, forming a part thereof.

Figure 1 is a front view, or side elevation, of the combined door and push-grille, showing my new design.

Figure 2 is a top plan view of the grille itself.

The essential feature of my design resides in the push-grille, shown in full lines.

I claim:

The ornamental design for a combined door and push-grille, substantially as shown and described.

DALLAS EMERY WALKER.
